PLASTERER'S TROWEL

Harry Oscar, New York, N. Y.

Application January 16, 1947, Serial No. 722,408

4 Claims. (Cl. 72—136)

1

This invention relates to plasterer's trowels and more particularly to trowels which are to be used to form smooth plaster guide strips immediately adjacent to door, window or other openings.

In forming a plaster guide strip immediately adjacent a door or window opening, the conventional plasterer's trowel does not normally permit the achievement of a true level surface relative to the trim member of the door or window frame. Accordingly, it is an object of this invention to provide an improved plasterer's trowel which is adapted to be used in a manner which will insure a level plaster surface or guide strip immediately adjacent the trim of a door or window opening and the like.

Another object of this invention is to provide a trowel of the character described which is adapted to slidably move with respect to a fixed surface, such as the trim member of a door frame, window frame or the like and to simultaneously form the plaster adjacent the fixed surface into a smooth, plane guide surface.

Another object of this invention is to provide in a trowel of the character described, contoured guide plans which is complementary to a fixed surface such as the molded trim member of a door or window frame and the like, wherein the guide means is adapted to move slidably with respect to the fixed surface and to simultaneously clean the surface of the trim member over which it moves.

Yet another object of this invention is to provide in a trowel of the character described, a guide member adapted to move over the trim member of a door or window opening and the like, the said guide member having a smoothing member removably attached thereto and including interchangeable means for determining the smoothing level of the smoothing member with respect to the guide portions of the trowel.

Yet another object of this invention is to provide in a trowel of the character described, a smoothing member adapted to produce a level plaster surface or ground immediately adjacent a trim member of a door, window frame or the like, wherein a portion of the smoothing member is slidably engageable with at least a portion of the said trim member during the smoothing operation, thereby acting as a guide for the smoothing member.

Yet a further object of this invention is to provide in a trowel of the character described, a smoothing member having removably attached thereto a guide member which is adapted to slidably engage an elongated member which includes a level element. More particularly, the

2

elongated member is adapted to be secured at either end thereof over a wall surface in a manner to insure that the smoothing member produces a plane, level plaster surface or ground adjacent the elongated member.

Still a further object of this invention is to provide a strong, durable, compact, device of the character described, which shall be relatively inexpensive to manufacture, easy to manipulate, and yet practical and efficient to a high degree in use.

The invention accordingly consists in the features of construction, combinations of elements, and arrangement of parts which will be exemplified in the construction hereinafter described, and of which the scope of application will be indicated in the following claims.

In the accompanying drawing, in which is shown various possible illustrative embodiments of this invention;

Fig. 1 is a perspective view of the plasterer's trowel showing the component parts thereof in disassembled form;

Fig. 2 is a perspective view of the plasterer's trowel, shown in Fig. 1, in assembled form;

Fig. 3 is a perspective view of a plasterer's trowel embodying the invention and illustrating a modified form of the invention;

Fig. 4 is an enlarged cross sectional view of the plasterer's trowel shown in Fig. 3;

Fig. 5 is a perspective view of the plasterer's trowel embodying the invention, in use;

Fig. 6 is a perspective view of a plasterer's trowel embodying the invention and illustrating a modified form of the invention;

Fig. 7 is a detailed cross sectional view of the guide and blade portion of the trowel shown in Fig. 6;

Fig. 8 is a perspective view showing the under surface of the guide and blade portion of the trowel shown in Fig. 6;

Fig. 9 is a front view showing the plasterer's trowel of Fig. 6, in use; and

Fig. 10 is a detailed cross sectional view of a plasterer's trowel embodying the invention and illustrating a still further modified form of the invention.

Referring now in detail to the drawing, 10 designates a plasterer's trowel embodying the invention. The trowel 10 comprises a guide member 11 made of metal or the like, a smoothing member 12 made of wood or the like, and fastening screws 13 for removably securing the smoothing member 12 to the guide member 11.

55 The guide member 11 comprises a flange portion 14 having threaded openings 15 formed in

end portions thereof. Extending from the flange 14 and at an angle thereto is a narrow wall 16 coextensive in length with the flange. To a mid portion of the wall 16 is secured a handle 17. The handle 17 includes a base portion 18 which may be welded or otherwise secured to the wall 16. A handle member 19, extending in spaced, parallel relationship to the base portion 18, is interconnected thereto at one end by a member 20.

Extending outwardly and downwardly from the wall 16 is a guide portion 21 which is of suitably contoured cross section. The guide portion 21 is coextensive in length with the wall 16. The specific cross section of the guide portion 21 of the guide member 11 is complementary to the molded trim member of a door frame, window frame or the like. The cross section shown in Figs. 1 and 2 is typical of but a single type of a door buck. It is apparent that the contoured guide portion 21 may be formed to suit any of the door or window frame trims conventionally used.

The smoothing or trowel member 12 comprises a rectangular block of wood or the like material, having a length substantially equal to the length of the flange 14 and having vertical edge surfaces 22, 22a equal in thickness to the height of the flange 14. The block 12 is formed with a pair of through openings 23 which extend from edge 22a to edge 22. The block 12 is removably secured to the member 11 by means of the screws 13 which pass through the openings 23 in the block 12 and screw into the threaded openings 15 in the flange 14. It will be apparent from a consideration of Fig. 2 that the through openings 23 are located between the flat surfaces of the block 12 so that when the block is secured to the member 11, the lower flat surface of the block is coextensive with the lower edge of the flange 14.

It is desirable to form plaster guide strips having a predetermined level with respect to the edge portions of the adjacent door or window trim. Accordingly, there is provided means for regulating the level of the smoothing surface of the trowel member with respect to the guide member. To this end, the block 12 is provided with additional through openings 24 which extend from the edge 22a to the edge 22 of the block and which are closer to one surface of the block than the other. Further sets of openings may be formed in the block at other selected locations whereby a different adjustment may be made to provide the desired level relationship between the smoothing member and the guide member.

In Fig. 3 there is shown a trowel embodying the invention and illustrating a modified construction. The trowel 10a comprises a guide member 30 and a trowel blade or smoothing member 31 detachably secured thereto. The guide member 30 comprises a planar edge portion 32 from which extends a contoured portion 33 coextensive in length with the edge portion 32. The contoured portion 33 includes arcuate and other molded sections corresponding to the molded trim portions of door bucks, window frames and the like. It is understood that the guide member 30 may be provided in various molded forms to complement any one of the molded trims conventional in the door and window frame art. The planar edge portion 32 of the guide member is formed with openings 34 at either end thereof for the purpose hereinafter described.

The trowel blade or smoothing member 31 com-

prises a substantially rectangular sheet of relatively thin metal or the like 35. A planar edge portion 36 is interconnected to the sheet 35 by a wall or flange 37 which extends at right angles to edge portion 36 and sheet 35. The sheet 35 and the edge portion 36 are in offset, parallel relationship to each other. The edge portion 36 of the blade 31 is formed with through openings 38 at either end thereof. A handle 39 is secured in any suitable manner to the edge portion 36 of the blade in spaced relationship thereto through a member 40, as shown in Fig. 3.

The trowel blade or smoothing member 31 is detachably secured to the guide member 30 by means of flat headed screws 41 passing through the openings 34 in the edge portion 32 of the guide member and the aligned openings 38 in the edge portion 36 of the blade member 31 and secured by nuts 42. It is often desirable to regulate the level of the plaster adjacent the door or window trim with respect to the edge of the trim. Accordingly, means is provided to permit the trowel to smooth the plaster to any desired level with respect to the trim adjacent thereto. To this end, removable shim elements 43 formed with through openings 44 are provided. The shim elements 43, which are in selected thicknesses, have a length and width substantially equivalent to the corresponding dimension of the edge portion 36 of the smoothing member 31 and edge portion 32 of the guide member 30. By interposing shim elements of the proper thickness or combination of thicknesses between the superposed portions of the guide and smoothing members with the screws 41 passing through the openings 44 in the shim elements which are aligned with openings 34 and 38, as shown in Fig. 4, the relationship of the blade 35 with respect to the guide member 30 is established. This in turn permits the determination of the level of the surface of the plaster strip adjacent the door or window frame when the trowel is used as shown in Fig. 5. Since the shims 43 are of the same width as the edge portion 32 and the edge portion 36, the flange 37 has contacting engagement with the side edges of the shims as well as the edge of the guide and this causes the guide and the blade to be effectively braced against tilting movement relative to each other.

In using the trowel shown in Figs. 3 and 4 it is only necessary to select the proper shims 43, assemble the guide member and the blade member with the interposed shims and secure the assembled parts by means of the screws 41 and nuts 42. The guide member 30 is selected to complement the particular molded trim surface upon which the trowel is to operate.

Frequently, the trim of the window or door frames becomes encrusted with plaster or other foreign matter. In using the trowels embodying the invention herein, the guide members act as a cleaning means as the guide member moves over the surface of the trim. The leading edge of the guide member is effective in removing plaster and the like which may be adherent to the surface of the door buck, window trim or the like.

In Fig. 6 there is shown a trowel embodying the invention and showing a further modification of the invention. The trowel 10b is adapted to be used for forming plaster guide strips on wall or ceiling surfaces. The strips are relatively narrow in width and are arranged at suitably spaced distances along the wall or ceiling. When the ground strips are formed, the spaces

between the strips are covered with plaster and are leveled by the use of a guide bearing on the strips previously formed. The trowel 10b comprises a guide member 50 to which is detachably secured a trowel blade or smoothing member 51. The combined trowel blade and guide is mounted for slidable movement on an elongated member 52. The guide member 50 comprises a substantially rectangular sheet of metal or the like 53 having downwardly extending flange portions 54 along the sides thereof. Each of the flange portions 54 has an inwardly extending edge portion 55 for the purpose hereinafter described. A handle 56 is secured to a mid portion of the guide 51. The handle 56 comprises a base portion 57 which is welded, screwed or otherwise secured to the sheet 53 of the guide member. A handle member 58 extends in spaced, parallel relationship to the base portion 57 and is interconnected at one end thereto by a member 59. The sheet 53 of the guide member is formed along one edge thereof adjacent the flange 54, with openings 60, for the purpose hereinafter described.

The smoothing blade 51 comprises a substantially rectangular portion of sheet metal or the like 61 having a slightly downwardly curved side edge portion 63. From the opposite side of the rectangular portion 61 there extends downwardly a flange 64. Extending upwardly from the lower edge of the flange 64, is a wall 65 from the upper edge of which extends outwardly a wall or edge portion 66. The wall 66 extends in parallel relationship to the rectangular portion 61 of the smoothing member. The forward and rearward ends of the rectangular portion 61 have upwardly curved edge portions 67. The wall 66 is formed with through openings 68 for the purpose hereinafter described.

The guide 50 and the blade 51 are detachably secured together by means of flat head screws 69 which pass through the aligned openings 60 and 68 in the guide and blade members respectively, and engage nuts 70. The level of the blade 52 with respect to the guide 50 may be adjusted by the use of shim elements 69a formed with openings 69b therein, interposed between the edge of the guide member and the wall 66 of the blade 51 and the side edges of the shims are engaged by the flange of the blade to brace the blade in the manner previously described.

The elongated member 52 is substantially rectangular in shape and may be made of wood, metal or the like. The member 52 is formed along its opposed edge portions with grooves 71. The guide member 50 is adapted to slidably move on the member 52 with the inturned edge portions 55 of the guide engaging the grooves 71 of the member 52. The member 52 further includes level elements of the spirit bubble type or the like 72, mounted on appropriate portions of the member as shown in Fig. 6, for the purpose hereinafter described.

In using the trowel 10b, the member 52 is temporarily secured to a wall surface by means of fastening elements such as nails, screws and the like in a vertical position as shown in Fig. 9. The level bubble 72 on the member 52 is used to properly level the member with respect to the wall surface. The guide 50 together with the smoothing blade 51 slidably moves on member 52, thereby forming a level plaster guide strip immediately adjacent the member 52. The member 52 is then detached from its position on the wall and is secured to the wall surface

in a new position suitably spaced from its original position, and the operation is repeated. When a number of guide strips have been thus formed, plaster is applied to the wall surface on portions intermediate the guide strips and is suitably leveled using the guide strips in conjunction with a leveling tool or straight edge. It is to be noted that the blade 61 will form a plaster guide strip having one edge formed with a slightly rounded corner due to the curved edge 63 of the blade 61. This facilitates the bonding of the intermediate portions of plaster with the guide strips formed by the use of trowel 10b. The upwardly turned portions 67 on the blade 61 facilitates the sliding movement of the blade over the plaster particularly when lumpy spots of plaster are encountered.

When it is desired to apply plaster guide strips to the corner portions of a room, trowel 10c may be used. The guide 50 with the shims 69 is similar to that shown in Fig. 7 and is detachably secured to a special trowel blade 80, as shown in Fig. 10. This blade comprises planar smoothing portions 81, 82 which are at right angles to each other. A wall or flange 83 extends upwardly from smoothing portion 81 and a wall 84 extends downwardly and inwardly from smoothing portion 82. An edge portion 85 extends outwardly from flange 83 to form a strip portion which is formed with openings 86 to receive bolts, whereby the trowel blade 80 may be detachably secured to the guide 50 with the flange 83 bearing against the guide and shims interposed between the guide and the edge portion 85. End walls 87 interconnect the planar smoothing portions 81, 82 and the walls 83, 84. In using this type of trowel blade, the member 52 is secured to the wall surface adjacent the corner to be plastered. The movement of trowel blade 80 and the guide 50 permits plaster to be smoothly applied on the two wall surfaces defining the corner and to thereby simultaneously produce guide strips on the intersecting wall surfaces. The end walls 87 on the blade 80 prevent plaster from getting into the hollow portions of the trowel blade.

It is understood that the trowels 10b and 10c may be used on ceiling surfaces as well as on wall surfaces.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

1. In a device of the character described, a guide member, a smoothing member having an edge portion thereof disposed in superposed relation with respect to the adjacent edge portion of the guide member, means for detachably securing the superposed edge portions together, and shim members interposed between the aforesaid superposed edge portions, whereby the level of the smoothing surface of said smoothing member may be adjusted relative to said guide member.

2. In a device of the character described, comprising a guide member having a contoured surface adapted to cooperate with the corresponding

portion of the trim of a door or window frame, a planar surface portion extending from said contoured surface, a smoothing member comprising a blade portion and an edge portion, said edge portion and said blade portion being in offset and parallel relationship to each other, the edge portion of said smoothing member and the planar surface portion of said guide member being in superposed relation and detachably secured together, and shim members lying between the superposed portions, whereby the level of the smoothing surface of said smoothing member may be adjusted relative to said guide member.

3. A plasterer's trowel comprising a member provided with a flat flange, an irregular shaped portion extending from one side of said flat flange, a second member comprising a flat flange superimposed with respect to said first flat flange and having a shoulder extending at right angles to said flanges, and a flat portion extending at right angles to said shoulder and parallel to said flanges, means to attach said flanges together and a handle fixed to said flanges, the means for attaching said flanges together comprising fastening members passing through openings in said flanges and one or more shims between said flanges.

4. A plasterer's trowel comprising a guide having an innerside edge portion formed with threaded openings spaced from each other longi-
